TRACTOR-DRAWN CORRUGATOR

Clark L. Roberts, Nampa, Idaho

Application February 25, 1947, Serial No. 730,839

4 Claims. (Cl. 97—55)

1

This invention relates to improvements in corrugators of that type designed for use in connection with a power tractor.

One of the objects of the present invention is to provide a tractor-drawn corrugator in which the shovels are regulated by depth controlled levers constructed and arranged to apply pressure to both sides of the machine whereby all of the shovels will operate at a uniform predetermined depth.

A further object of the invention is to provide a corrugator in which the shovels are arranged for lateral adjustment relative to each other with the press rolls likewise relatively adjustable for cooperation with the shovels.

Other objects of the invention reside in the provision of means for hoisting the corrugator as a unit to facilitate the operation of the device in making turns at the end of the row, the hoisting device being actuated by suitable power provided from the tractor as through the medium of a hydraulic lift and suitable connecting linkage.

A further object of the invention is to provide a device of the type in question in which the mechanism for controlling the assembly is readily operable by the driver of the tractor from his seat on the latter vehicle.

Other features and details of construction such as the use of hardwood bearings for the wheel and axles and wings for the shovels to keep the corrugate open until entered by the present wheel are shown, described and claimed and form a part of the present invention.

Reference will be had to the accompanying drawings forming a part of the specification and wherein like characters of reference designate corresponding parts throughout the several views, in which:

Figure 1 is a side elevation of the invention.

Figure 2 is a top plan view.

Figure 3 is a fragmentary sectional view of the control lever for the shovels.

Figure 4 is a detail showing the transverse axle plate providing adjustment of the shovels.

Figure 5 is a detail showing the construction of the base of the quadrant in detail.

Figure 6 is a transverse section showing the wooden bearing for the wheel.

Figure 7 is a perspective showing the detail of the linkage of one of the shovels.

Figure 8 is a longitudinal section through one of the shovels.

Figure 9 is an elevation showing the scraper mechanism.

Figure 10 is a perspective of a shovel assembly.

Figure 11 is a top plan view showing a modified form of corrugator lift mechanism; and

Figure 12 is a side elevation of the structure shown in Figure 11.

2

The corrugator embodies a main frame formed of front angle bar 1 and rear angle bar 2 with suitably spaced connecting angle bars 3 welded, bolted or riveted at their ends 4 to the transverse front and rear frame members 1 and 2, thus providing a rigid structure for supporting the various parts. The shovels for forming the corrugates or furrows are interposed between the connection angle bars 3 and are arranged medially of these bars as more clearly shown in Figure 2. In the present illustration four of these connecting angle bars 3 are provided, each equally spaced to provide for the arrangement of the shovels indicated by reference characters 6 and 7.

It will be noted that the outer shovels 6 are located outside of the outer angle bars 3, although this arrangement could be modified. Both the front and rear angle bars 1 and 2 face rearwardly, with the connecting angle members 3 welded or bolted to the uprights of the angles. The forward end of the connecting angle members 3 have their lower flanges at their front ends riveted to the lower horizontal flange of the front frame member 1 by rivets indicated by numeral 8. The rear ends of the spacing angles 3 are welded and bolted against the outer face of the upright of the rear frame member 2. It will be noted that in the disclosure where four of these spacing angle members 3 are provided, their arrangement is reversed at opposite sides of the frame so that there is provided two pairs of spacing angles 3 at each side of a medial line through the frame, with each pair of spacing angles 3 having their lower flange facing inwardly towards the opposite pair.

For supporting the shovels 7 adjustably along the front frame member 1, I have provided, as shown in Figure 4, the angular plates 9 which have their radial legs 10 bolted by means of bolts 11 through perforations 12 drilled at spaced intervals throughout the length of the upright flange bar 1. By this arrangement the shovel arm 14 may be clamped between the angles 9 by bolts 15 at any desired position along the front frame member 1. Thus the spacing of the shovel 7 will be selective in accordance with requirements and wishes of the operator of the machine.

Referring now to Figure 8 it will be noted that the shovels 7 are fixed to the depending portion 15 of the arm 14 by means of bolts 16, these bolts extending through the forward front portion of the shovels 7, so that the shovel and the wings 18 supported thereby are clamped as a unit, the shovel cutting the ground as better shown in Figure 7, while the wings hold the spread earth pending the fixing the soil by the following press wheels 20. Each of the arms or hangers 14 are connected through the links 21 and 22 to

the square cross bar 23, the latter being fixed in the cast bushing 24 within the hangers 25 riveted or bolted to each one of the connecting angle bars 3 as shown in Figure 7. By this arrangement the shovels, as a unit, will be raised and lowered by operation of the control arm 26. The control arm 26 is fixed to the radiating arms 27, the extremities of which are secured to the forward ends of a pair of spaced clamp members 28. These clamp members are suitably secure, as by being split and bolted, to the transverse square cross bar 23, and extend rearwardly from this cross bar a suitable distance to provide proper leverage for the ends of the compression bar 29. The compression bar 29 projects from a medial point of each of the members 27 to the rear extremities of the clamps 28 and are bolted to the rear portions of these clamps by bolts 29'. It will be noted that the bolt 28' which secures the clamp to the square cross bar also forms the securing bolt for the rear ends of the radiating arms 27 and secure these arms to the clamps. This structure provides a control capable of exerting a substantial resilient pressure at predetermined spaced points along the length of the bar 23, the members 29 forming an extension for the arms 27 to provide, in connection with the clamp members 28, increased forces for performing the desired function. By this arrangement the bar 23 is capable of being rocked in its bearings 24 and the shovels are under substantial pressure during use of the apparatus. The control arm 26 is swung vertically and locked in adjusted position by cooperation and use of the quadrant 30, the latter being provided with notches 31 and having its lower end clamped to the front frame member 1 by angular clamps 32 and bolts 33 as shown in Figure 5.

In Figure 3 the locking means for the control member 26 and through the control arm the two radiating arms 27 is shown to include the ratchet element 34, normally urged inward in engagement at its end 34' with the ratchet bar 30 by means of a spring 39. The spring 39 is interposed between the pin 27 and the angular extension plate 40, the latter extension 40 projecting from the guide plate 40' having diagonal marginal portion 36 fixed to one of the radiating control arms 27. The main control arm 26 projects transversely of the structure and parallel to the ratchet arm 34 from its plate-like body portion 26'. The marginal edge of the plate structure 26' is flanged angularly outward as at 27' to lie flush with the other radiating arm 27 and is attached to this arm by welding or otherwise and in the same manner that the angular flange 36 is secured in position to its arm 27. The housing formed by the spaced plates 40' and 26' abut against the lateral side walls of the quadrant ratchet 30 and retain the latter against lateral displacement. The walls 26' and 40' are formed with slots 35 and 38 through which the inner lateral off-set portion 34' of the ratchet 34 extends. It will be noted that the slots 35 and 38 have their inner ends defined at 41 and 42 in a plane substantially flush with the inner faces of the recesses of the quadrant. It will be noted that all of the parts of the control mechanism are removable for replacement and repair.

After moving the ratchet arm 34 (Fig. 3) against the tension of spring 39 to disengage the same from one of the notches 31 of the quadrant, control arm 26 can be raised and lowered to shift the shovels 7 on their supporting arms 14, so that these shovels may cut a furrow of predetermined

depth. Due to the fact that control arm 26 is provided with a spaced radiating connecting arms 27 which engage the supporting bar 23 through suitable leverage 22 at each end of this bar, the adjustment of the shovels at each end of the bar remains constant, and substantial pressure on these shovels throughout the entire length of the supporting bar is maintained with a great deal of accuracy.

A plurality of press rolls 20 are mounted on an axle 43 supported in wooden bearings 45 in the bearing housing 46, the latter being bolted to the horizontal angles of the longitudinally extending angular bars 3 by bolts 47. The horizontal flanges of the connecting angles 3 may be provided with a series of perforations to permit forward or rearward adjustment of the axle 43 supporting the pressing rolls, this arrangement permitting the use of different types of shovels or pressing rolls in instances where a change in these structures is desirable (Figure 6). The pressing rolls are adjustable longitudinally of the axle 43 to properly associate the rolls with their shovels. Rearward of the pressing rolls is a shaft 50 which extends through openings formed in the hangers 51 welded to the vertical flanges of the connecting angles 3. These hangers 51 are merely plates with aligned openings through which the rod 50 extends. Supported on the rod are a plurality of clearing scrapers 52, the outer faces of which contact the peripheral faces of the presser rolls 20 to keep the latter clear of mud and dirt. The contact between the scrapers 52 and the rolls 20 is relatively light, being maintained by means of a spring 53 as clearly shown in Figure 9.

The hitch between the corrugator and the tractor includes the laterally angled arms 55 and 56, these arms being bent at their outer ends 57 and bolted by means of bolts 58 to spaced angle connectors 3 (see Figures 1 and 2). The forward ends of the connecting links 56 are bent to flatly engage the angle brackets 59 of the tractor and are bolted thereto by bolts 60 as shown. The hitch structure including the draft arms 55 and 56 can be elevated vertically by means of the adjusting nuts 62 which are threaded on a vertical bolt carried by the bracket 63 and engaged within the tubular portion 63' and support the draft arms.

A hydraulic lift 65 suitably mounted on the tractor A operates the hoist mechanism for raising and lowering the corrugator in and out of the ground. This raising and lowering mechanism includes the swinging arm 66' pivoted in the usual manner to the tractor at 65', the hydraulic hoist 65 swinging the arm on its pivots. Suitable adjusting links 69 are pivoted to the arm 66' and cooperate with the chain 67 to swing the corrugator forwardly on its hinged pivotal connection 60. The chain 67 has its free end adjustable in the key slot of the link 69, this chain having two branches which are fixed to the upper ends of the uprights 68. The uprights 68 are rigidly secured to the front bar 1 of the corrugator, and preferably at a point in this frame structure braced by the extremities of the spacer elements 3. To distribute the forces during the lifting operation arms 70 are provided and connect the frame at spaced points with the upper portions of the uprights 68. Additional braces may be interposed between the uprights 68 or between these uprights 68 and the frame to prevent distortion of these parts during the lifting operation.

Referring now to Figures 11 and 12 I have shown a modified form of tractor lift. In these figures the conventional swinging tractor lift arm is illustrated by reference character M, this arm being operated in the usual manner from a suitable source of power. A pair of adjustable converging connections 68a are secured at their lower ends to the side frame members 3 of the corrugator structure, substantially medial of the structure and extend forwardly to a point immediately forward of the corrugator assembly. It will be noted that the connections 68a are of sectional form, each section being provided with a series of bolt openings which may be registered to permit relative adjustment of the parts prior to bolting together by means of the bolts 75. The forward ends of these connectors are secured to the inclined adjustable telescoping tubular legs 65, these legs being pivotally connected at 76 to the tractor frame as shown in Figure 12. Link plates 71 are clamped to the connectors 68a and the adjustable legs 65 by means of the bolts 78 and link these parts together for pivotal movement. The link plates 71 are generally of the structure of the link plates 69 in the other form of this invention and include a key slot for adjustable association with the chain connector 67. The chain is connected at one end to the connecting arm 66 and the forward end of the latter is formed with a plurality of openings 79 for adjustable connection by means of a bolt 79' or otherwise with the tractor lift arm M. By this mechanism the swinging of the tractor lift arm M will result in a swinging or lifting movement of the corrugator structure on the pivots 76' by means of which the tubular legs 65 are pivoted to the tractor frame.

By means of the foregoing I have provided a tractor-drawn corrugator, well-balanced and easy running and sufficiently strong and rigid to work equally well in all kinds of soil. By means of the depth control mechanism it is possible to apply to both sides of the machine pressure which will hold all the shovels at a uniform depth during all operations. The wheels and axle assemblies are rigid and will turn in hard wood bearings secured to the frame of the machine as shown. By this means it has been possible to eliminate the dropping of soil into the bearing of the wheel which is objectionable in machines of this character. The shovel which is of special design has been constructed to give a streamlined effect, thereby permitting the maintenance of greater speed. Wings have been provided for the shovels which keep the corrugate open until entered by the press wheel. This shovel structure forms a part of another application.

By means of the present assembly it is possible that all adjustments can be readily made and that the corrugator can be built to provide any predetermined number of rows. The present illustration is designed to work five rows; however, it will be noted that the number of rows and their spacing may be readily provided for through the adjustment and interchange of parts.

What I claim is:

1. In a corrugator, a main frame including spaced forwardly and rearwardly extending parallel frame members, a rockable cross bar supported medially of said frame, shovels pivotally supported on said frame, link mechanism connecting said rockable bar to each of said shovels whereby said shovels may be raised or lowered 75

upon rocking of said bar, a pair of diverging control arms fixed to said rockable bar at their free ends, a quadrant fixed to said frame forwardly of said bar, guide means slidably connecting the forward end of said control arms and quadrant to permit raising and lowering of said arms on said quadrant, means for locking said arm in adjusted position, clamps fixed to said bar and extending rearwardly thereof, means carried by said arms for applying pressure to said bar at points spaced forwardly and rearwardly of the bar, a rotatable axle carried by the frame rearward of said rockable bar, and a plurality of press wheels fixed to said axle and longitudinally adjustable with respect to the same.

2. In a corrugator, a main frame including spaced forwardly and rearwardly extending parallel frame members, a rockable cross bar supported by the frame, shovels pivotally supported by said frame forwardly of said cross bar, link mechanism connecting said rockable bar to each of said shovels whereby said shovels may be raised or lowered upon rocking of said bar, a pair of control arms for said rockable bar, said control arms being connected to said bar at their rear ends at spaced points and being connected together at their front ends, a quadrant fixed to the frame forwardly of the bar, guide means for adjusting the connected front ends of said control arms on said quadrant, means for locking said arms in adjusted position, resilient means carried by said control arms for applying pressure to said rockable bar at points spaced forwardly and rearwardly of said bar, and press wheels positioned rearwardly of said shovels.

3. In a corrugator, a frame including spaced transversely extending front and rear members, a plurality of spaced parallel frame members connecting said front and rear frame members 40 to define a plurality of rectangular frames, a shovel arranged in each of said frames and pivotally supported on the front frame member, a rockable cross bar supported by said parallel frame members, link mechanism connecting said shovels with said rockable bar whereby said shovels may be raised or lowered upon rocking of said bar, a pair of control arms fixed to said rockable bar at their rear ends, said control arms being connected at their front ends, a quadrant fixed to said frame forwardly of the bar and associated with said control arms to permit the same to be locked in adjusted position on said quadrant, a rod connected to the upper part of each of said control bars forwardly of the rockable bar and extending rearwardly of said rockable bar, means connecting the free end of said rods to said rockable bar, a rotatable axle carried by said frame rearwardly of the rockable bar, and a plurality of longitudinally adjustable press wheels fixed to said axle.

4. The substance of claim 3 characterized in that the means for applying pressure to the rockable bar includes resilient connections.
